To all whom it may concern:

Be it known that I, Edna Breer, a citizen of the United States and a resident of the city of New York, in the county of New York and State of New York, have invented a new, original, and ornamental Design for a Dress Ensemble, of which the following is a specification, reference being had to the accompanying drawing, constituting a part thereof.

The characteristic feature of my dress ensemble resides in the specific embroidery on bolero jacket in association with the dress as shown.
